UNITED STATES PATENT OFFICE.

CHARLES E. BONINE, OF MELROSE PARK, PENNSYLVANIA.

CONCENTRATOR.

Application filed May 10, 1923. Serial No. 637,989.

To all whom it may concern:

Be it known that I, CHARLES E. BONINE, a citizen of the United States, residing at Melrose Park, in the township of Cheltenham, in the county of Montgomery and State of Pennsylvania, have invented certain new and useful Improvements in Concentrators, of which the following is a specification, reference being had to the accompanying drawings.

My invention relates generally to concentrating apparatus in which the separation of the ingredients of a mixture or aggregate is effected through selectivity made possible by differences in specific gravity of the particles, and more especially to apparatus operative upon the dry principle, that is to say, without necessitating the use of water or other liquid for removal of the waste or gangue.

The more important objects of my invention are to enable sharper and more efficient dry separation than possible with apparatus heretofore designed for a similar purpose, and to enable simultaneous concentration of the ingredients of complex mixtures or aggregates thereby obviating the necessity for successive treatments.

Other subsidiary objects and attendant advantages will become apparent from the detailed description which follows of a typical embodiment of my invention, and its scope is readily seen from the appended claims.

In the drawings, Fig. I is a perspective illustration viewed from the front of a concentrating apparatus conveniently embodying my invention.

Fig. II is a similar illustration of the apparatus viewed from the rear.

Fig. III is an illustration in plan of the vibrating table forming part of the apparatus, a portion of the table cover being broken away for better illustration of certain details which would otherwise be hidden.

Fig. IV is an illustration of the table partly in side elevation and partly in longitudinal section, the section being taken as indicated by the arrows IV—IV in Fig. III.

Figs. V and VI are cross sectional views of the table taken respectively as indicated by the arrows V—V and VI—VI in Fig. III; and

Figs. VII and VIII are detail views of the

outlet nozzles through which the separated materials are discharged from the apparatus.

Referring first more particularly to Figs. I and II of the drawings, it will be observed that the apparatus comprises a framework, comprehensively designated by the numeral 1, designed for the support of the concentrating table 2. As shown, this table 2 is substantially of rectangular, or more accurately speaking, of oblong configuration, and in order that it may be reciprocated or vibrated in a longitudinal direction, a bar or rod 3 secured along the center of its bottom, (see Fig. II) is slidably sustained by bridge bearings 4—4 arched across a pair of spaced parallel channel beams 5—5 which rest upon transverse blocks 6—6 bolted or otherwise rigidly secured to the top platform 7 of the framework 1. Any suitable head motion device 8 capable of inducing a return shog more rapidly than forward movement and with provisions for frequency regulation, may be employed for vibrating the table 2 with which it is operatively connected by means of a coupling link (not shown). An electric motor 10, coordinated by means of a belt 11 with a pulley 12 on the shaft of the head motion device 8, serves in the present instance to drive the latter at a constant rate of speed. The table 2 may be angularly tilted about the axis of the bar or rod 3 as a fulcrum, an adjustment means being provided in the form of a hand screw 13 which is supported for rotation jointly by the channel beams 5—5 and engages a lever 90 or arm 14 fixed to and depending from said bar or rod.

Attention is now directed to Figs. III to VI inclusive which show the details of the table 2. From these illustrations it will be observed that the table 2 comprises an extended surface or deck 15 with a series of ruffles 16, which, although disposed generally longitudinally, are convergent toward the left hand or discharge end of said table. The deviation may vary from the true horizontal of the lowermost rifle 16 to some thirty degrees or more depending upon the character of the material being treated. As a result of such divergency of the ruffles 16—16, it follows that the grooves or valleys 17 between them become gradually more and more attenuated as they approach the discharge end of the table. It is also to be noted from Fig. IV that the upper edges of 110

the riffles 16 decline gradually from maximum depth at the right hand or receiving end of the table to a comparatively shallow depth at the discharge end. The importance of these various characteristics will be fully explained later in the course of the description of operation of the apparatus. Ordinarily in practice, the surface or deck 15 would be constructed of wood, preferably covered with linoleum or other material affording a uniformly smooth surface, but, if desired, the same can be made of cast or sheet metal suitably corrugated to provide the desired arrangement of riffles 16 and grooves.

The table 2 furthermore has a perimetrical wall 20 appropriately braced by corner angles 21, and affording conjointly with an insert cover member 22, a shallow interspatial closure 23 above the surface or deck 15 for passage of air for conveying or carrying off the gangue or waste from the material being concentrated. The cover member 22 is preferably glazed as conventionally represented at 24 in Figs. I and III so that the progress of the material over the table surface is at all times open to observation. In order that the cover member 22 may be vertically or angularly adjusted relative to the deck or surface 15 either locally or as a whole, I have provided for its support at the corners by set screws 25-25 appropriately anchored in the table structure and equipped at their lower projecting ends with knurled heads 26 for finger manipulation. The side and bottom edges of the cover member 22 are sealed against air leakage by marginal strips 27 of rubber or the like maintained by virtue of their inherent resiliency or springiness in effective contact with the insides of the contiguous sections of the perimetrical wall 20. The upper edge (Fig. III) of the cover member 22 is however spaced from the wall section at that side of the table 2 with consequent provision of a co-extensive slot 28 which serves as an air inlet for the interspace 23.

Air is exhausted from said interspace 23 through a series of ports or outlets 29 arranged at regular intervals along the lower longitudinal side of the table 2. As a result of this construction, the air is drawn laterally across the path of the movement of the material on the deck or surface 15, the lighter ingredients or displaced waste being thereby conveyed or directed to a trough or launder 30 provided at the front or air outlet side of the table 2. As shown to the best advantage in Fig. V, the trough or launder 30 is recessed relative to the surface or deck 15 and is amply proportioned as to width and depth. This amplification is not only important from the standpoint of capacity, but determines a sudden velocity decrease in the air flow thus facilitating precipitation

of the waste or gangue into the bottom of the trough or launder 30. The suction ports 29, it will be noted, are well elevated above the bottom of the trough or launder 30, and are further protected by baffle plates 31 and 32 designed to prevent efflux of the gangue through them. Tubes 33 of rubber or other flexible material capable of permitting free motion of the table 2, lead from the ports 29 to a common manifold 34 extending longitudinally of the table 2 and supported upon saddle brackets 35-35 of the framework 1. Air is in turn exhausted from the manifold 34 through a conduit 36 connected with a suction device 37 mounted on the lower platform 38 of the framework 1 and arranged to be driven by belt 39 from an electric motor 40. The outlet 41 of the exhaust blower 37 may be connected either to a dust separator or to some suitable depositary not shown.

The various concentrates liberated from the delivery end of the riffles 16 as herein-after noted, are collected in a series of hoppers 45-45 (see Figs. III and VI) arranged along the discharge end of the table 2, an additional end hopper 46 being provided for reception of the gangue from the trough or launder 30. The partitions 47 between these several hoppers 45-45 are mounted upon pivot shafts 48 which extend to the exterior of the table 2 and are fitted with suitable grasps 49 for finger manipulation. By the adjustability thus afforded, the partitions 47 may be positioned at different angles so as to vary the number of riffle ends included or comprehended between them which permits greater selectivity with regard to the various precipitates discharged from the riffled surface 15. The release from the several hoppers 45-45 may be collected in any manner found convenient, for example by means of individual tubes 50 leading to as many receptacles 51 suitably supported beneath them upon a shelf 52 projecting from one end of the framework 1. The tubes 50 are provided with outlet nozzles 53 constructed of flexible material such as rubber and with their ends flattened as best shown in Figs. VII and VIII of the drawings for valvular action permitting free efflux of the material, but, by responding to automatic closure under suction, preventing ingress of air.

The material to be treated is introduced in the apparatus through a hopper 55 which empties into a storage receptacle at the bottom of a housing 56 for a sprocket chain elevator 57 indicated for the most part in dotted lines in Fig. II. This chain elevator 57 has a series of buckets 58 which lift the material from the storage receptacle and subsequently deposit their contents upon a chute 59, supported at an inclination on an overhang 56a of the housing so as to dis-

charge into a funnel 60 which directs the material onto the deck or surface 15 of the table 2. The chute 59 is mounted upon its support with capacity for being shifted laterally so as to be overlapped more or less by the buckets 58 of the elevator 57. This provision affords a simple control for regulating the feed of the material, the excess released from the elevator buckets 58 dropping back into the storage receptacle. Any dust occasioned during the fall of the material is drawn out of the storage receptacle through a hose or conduit 61 (Fig. I) connected to the exhaust manifold 34 previously referred to. The elevator 57 may be actuated from a separate power source or by a sprocket chain connection 62 (Fig. II) with the shaft of the head motion device 8 by which the table 2 is vibrated.

Preparatory to starting the apparatus, the table 2 is first slightly tilted relative to the horizontal as suggested in Figs. I and II, by manipulation of the hand wheel 13 so that the aid of gravity is secured for assuring displacement of the gangue or waste laterally of said table, and the cover member 22 angularly adjusted relative to the deck or cover 15 by means of the set screws 25 after the manner shown in Figs. V and VI to predetermine a gradual decrease in the velocity of the air flow toward the trough or launder 30. With these preparations, the motors 10 and 40 are started to set the head motion device 8 and the blower 37 in operation. The dry mixture or aggregate (previously comminuted by grinding or milling) and introduced into the storage chamber in the bottom of housing 56 is continuously elevated by the bucket conveyor 57 and discharged, under guidance of the chute 59, to the funnel 60 whereby it is fed directly onto the surface or deck 15. As the operation proceeds, the chute 59 may be shifted laterally relative to the elevator buckets 58 to control the flow rate of the material to the table 2. The material thus discharged upon the surface or deck 15 is first arrested by the uppermost riffles 16-16, and, owing to the inclination of the table 2, and the declination of said riffles toward the discharge end of the table, spreads or distributes itself along them. Under the continuous agitation set up by vibration of the table 2, the material is not only progressed along the riffles 16-16, but stratified in the intervening grooves or valleys 17, the heavier particles in settling downwardly forcing the lighter ones to the top, (this action being enhanced by the attenuation of the grooves 17) thereby exposing them to the sweeping action of the laterally moving air flow passing through the interspace 23. The heaviest constituents of the mixture are thus retained by the uppermost riffles 16-16 and, owing to the comparatively greater slope of the latter, are discharged from the table 2 more quickly than the others. The transition of the remainder of the material from riffle to riffle, as a consequence of the gradual velocity decrease in the air and the gradual approach of the riffles 16-16 toward the horizontal downwardly declined end of the table 2, is entirely dependent upon the relative specific gravities of its constituents. The different substances are in this wise separated one from the other and eventually find their way into the hoppers 45-45 at the discharge end of the table 2, while the lighter particles hereinbefore referred to as the gangue or waste, are directed by the air flow together with the assistance of gravity, into the trough or launder 30 and from thence into the hopper 46. The declination of the riffles 16 from a maximum depth at the feed end of the table 2 to a minimum at the discharge end, insures finer gradation of the material and hence a sharper separation of the concentrates. Selectivity between the different concentrates may be had over a comparatively wide range through the adjustability of the partitions 47 of the hoppers 45-45, the latter collecting the concentrates and directing them through the discharge conduits 50 to the separate receptacles 51.

From the foregoing, it will be obvious that the concentrating apparatus of my invention may be employed in treating ores, minerals, in separating peanuts from their shells, slate from coal, as well as in separating chemical mixtures which would not admit use of water or other liquids on account of solvent action. The treatment of these various substances may, in order to secure the best results, require changes in the angular positioning of the table 2, rate of air flow, frequency of table vibration, or relative angular disposal of the riffles 16-16, but these may, within the scope of my invention, be readily made with the means hereinbefore described or with other known expedients suitable to the purpose.

Having thus described my invention, I claim:

1. A concentrating apparatus comprising a longitudinally vibratory enclosed table having convergent and gradually declining riffles for maintaining isolation of, and for guiding different extracted concentrates toward the discharge end of the table, a series of non-return outlets therefor, a complementary series of hoppers arranged along the table end to individually receive the different concentrates, and means for evacuating air transversely over the upper surface of said table.
2. A concentrating apparatus comprising a longitudinally vibratory enclosed table having convergent and gradually declining riffles for maintaining isolation of, and for

guiding different extracted concentrates toward the discharge end of the table, a series of flexible non-return outlets therefor, a complementary series of hoppers arranged along said table end to individually receive the different concentrates, said hoppers having partitions capable of angular adjustment for variation in the number of riffle ends comprehended between them, and means for evacuating air transversely over the upper surface of said table.

3. A concentrating apparatus comprising a table enclosed for the passage of evacuated air thereover to effect elimination of the gangue from the material being treated, a series of outlets for the concentrates leading from said table, said outlets having discharge nozzles of flexible material permitting free egress of the concentrates but preventing, through responsiveness to suction, ingress of air.

4. A concentrating apparatus comprising a longitudinally vibratory table having convergent and gradually declining riffles affording a surface effective to separate the constituent ingredients of the material being treated, a perimetrical wall extending about the table, a cover member affording in conjunction with said wall a closure over said surface, means for inducing flow of air through said closure in a direction laterally over the moving material, means whereby the cover member may be angularly adjusted relative to the table surface to determine a gradually decreasing velocity in the air flow to effect lateral spreading of the material and gradation of its ingredients in accordance with their respective specific gravities, and means whereby the separated concentrates are individually discharged from the aforesaid table under non-return action.

5. A concentrating apparatus comprising a longitudinally vibratory table affording a surface for progression of the material being treated, said surface having a series of longitudinally convergent and gradually declining riffles for guiding the material toward the discharge end of the table, an angularly adjustable cover for the table affording an enclosure, means for inducing a flow of air at a gradually decreasing veloc-

ity through the enclosure in a direction crosswise over the moving material to effect transition and separation of the various ingredients from riffle to riffle in accordance with their respective specific gravities, and non-return outlets controlling the discharge of the separated concentrates.

6. A concentrating apparatus comprising a longitudinally vibratory table having convergent and gradually declining riffles affording a surface for progression of the material being treated, an angularly adjustable cover for said surface affording an enclosure, means for inducing flow of air through the enclosure in a direction laterally over the moving material to remove the gangue from the latter, a launder along one side of the table into which the gangue is drawn, said launder being amply proportioned to determine a sudden drop in the velocity of the air for facilitating the precipitation of the gangue in said trough or launder.

7. A concentrating apparatus comprising a longitudinally vibratory table affording a surface for progression of the material being treated, an angularly adjustable cover for said surface affording an enclosure, a launder arranged along one side of the table, suction means communicating with an outlet in said launder and adapted to induce a flow of air through the closure aforesaid for elimination of the gangue from the progressing material, and baffles facilitating the flow of the gangue into the launder and preventing entry of the precipitate into the outlet aforesaid.

8. In a concentrating apparatus of the type described, the combination of a table having longitudinal riffles attenuated toward the discharge end thereof, a closure for said table, a launder along one side of the table, and a series of controllable hoppers at the discharge end of the table, each said hopper being formed with a flexible outlet having a flattened free end permitting efflux of material but preventing ingress of air.

In testimony whereof, I have hereunto signed my name at Philadelphia, Pennsylvania, this 4th day of May, 1923.

CHARLES E. BONINE.
